UNITED STATES PATENT OFFICE.

RICHARD SMITH, OF PHILADELPHIA, PENNSYLVANIA, ASSIGNOR TO
MACKELLAR, SMITHS & JORDAN, OF SAME PLACE.

DESIGN FOR PRINTING-TYPE.

Specification forming part of Design No. 7,102, dated January 6, 1874; application filed December 20, 1873.
[Term of Patent 7 years.]

B.

To all whom it may concern:

Be it known that I, RICHARD SMITH, (assignor to MacKellar, Smiths & Jordan,) of the city and county of Philadelphia, Pennsylvania, have originated and produced a new and original Design for Printing-Type, of which the following is a specification:

The nature of my design for printing-type is

fully shown in the accompanying typographic impression, to which reference is made.

What I claim as new is—

The design for printing-type, as shown.

RICHARD SMITH.

In presence of—

C. N. HUCK,
GEO. WM. WITHAM.
